UNITED STATES PATENT OFFICE.

WILLIAM LUMLEY, OF CHICAGO, ILLINOIS, ASSIGNOR TO FRANCES LUMLEY,
OF SAME PLACE.

PARTITION-SUPPORT FOR PIGEON-HOLES AND DRAWERS.

SPECIFICATION forming part of Letters Patent No. 397,866, dated February 12, 1889.

Application filed August 9, 1888. Serial No. 282,320. (No model.)

To all whom it may concern:

Be it known that I, WILLIAM LUMLEY, a citizen of the United States, and a resident of Chicago, in the county of Cook and State of Illinois, have invented certain new and useful Improvements in Partition-Supports for Pigeon-Holes and Drawers, of which the following is a specification.

This invention relates to improvements in partition-supports especially designed for use upon desks, to enable the dividing or partitioning of drawers and pigeon-holes into smaller compartments differing in size and shape from the permanent form of the desk, 10 and which is in the form of an attachment thereto, and therefore does not form a permanent portion of the desk, as do the ordinary cleats or division-strips generally used for this purpose, but is especially designed as an 15 improvement upon the invention set forth in my application for Letters Patent, Serial No. 252,015, filed October 11, 1887. In that application the support was shown as consisting of crimped, corrugated, or bent metal attached by means of tacks or otherwise to the 20 desk, but which presented along the edges of the support a series of openings in the spaces between the groove occupied by the partitions, thus not only leaving sharp edges 25 against which the hands might be bruised or cut and recesses in which would lodge dust and dirt, but also presented an unsightly appearance, which rendered the support objectionable for use upon a desk, especially in 30 pigeon-holes or other spaces where it would be constantly in sight.

The prime object of this invention is to improve the appearance of the support by closing the ends of the spaces adjacent to the 35 grooves occupied by the partitions, thereby giving a perfect finish to the support and rendering it rather an ornament than otherwise to the desk.

A further object is to provide improved 40 means for removably attaching the support to the drawer or pigeon-hole, whereby not only will a less number of tacks or similar fastening devices be required for securing it in place, but the support may be more easily 45 detached when found desirable, and without leaving marks that would mar or otherwise

detract from the appearance of the desk. I attain these objects by the devices illustrated in the accompanying drawings, in which—

Figure 1 represents a front elevation of a 55 portion of a desk, illustrating the manner of attaching my support to the pigeon-holes and drawers thereof; Fig. 2, a horizontal section of a portion of a drawer or desk-frame, taken through one of the grooves in which the partition is designed to rest; Fig. 3, a perspective view thereof; and Fig. 4, a face view of a portion of a drawer or desk-frame, more clearly showing the contour of the finished article. 60

Similar letters of reference indicate the same parts in the several figures of the drawings.

Referring by letter to the accompanying drawings, A indicates the walls of a drawer 70 or pigeon-hole, and B the removable supports, consisting of sheet metal crimped, stamped, or otherwise formed with projecting ribs C at regular intervals therein, with alternate spaces D between said ribs in which to insert 75 the partitions E, as more clearly shown in Fig. 1. These ribs C extend the entire length of the support, and are struck or crushed down onto the base of the support a short distance in from the edge, and extend at an 80 angle from the base to the top of the ribs, thus closing the ends of the spaces formed by said ribs between the grooves in which the partitions are inserted. This flattened portion of the support is then bent backwardly 85 along the edge in a line at right angles to the ribs, so as to lie obliquely to the base of the support, which angular portion F is inserted in a corresponding angular groove, G, formed in the face of the drawer or desk-frame, thereby preventing the detachment of the support from the desk by a direct strain at right angles to the base thereof, and may be then firmly secured in place against the 90 possibility of accidental detachment by means of small tacks H, inserted therein at the four corners thereof, or, if the strip is of any considerable height or length, by one or two tacks placed intermediate the corner tacks. 95

The flattening or stamping down of the 100 ribs along the edge of the support serves to materially strengthen and stiffen the entire

body of the support, but particularly the angular portion thereof, which is inserted into the groove in the desk, while at the same time it serves to close the ends of all of the 5 unoccupied spaces at the ends of the ribs between the grooves in which the partitions are inserted, thus giving to the support a finished and rather ornamental appearance, besides dispensing with the sharp and unsightly edges 10 which would otherwise be presented, and which are a constant source of danger to the hands, which are liable to be cut, scratched, and otherwise injured thereby when thrust into the pigeon-hole or drawer.

15 The essential feature of this invention is the closing of the ends of the spaces between the grooves in which the partitions are inserted in a cheap and effectual manner, thus adapting crimped or bent sheet metal for use 20 as a support for the partitions; and, being practically engaged in the manufacture of desks and other office furniture, I am qualified to state that unless the ends of these spaces can be closed, and in a cheap and 25 effective manner, such removable supports have little commercial value and will be used only to a very limited extent, and further, that it is equally important that the support shall be of cheap material and ornamental in construction and manufacture, as well as combine 30 all of the advantages of the ordinary permanent wooden strips, all of which my device

possesses in the highest degree, and, in addition, has the advantage of detachability without disfigurement of the desk and the capability of a greater number of divisions in a given space than is possible with the old form of permanent supports.

Having described my invention, what I claim, and desire to secure by Letters Patent, 35 40 is—

1. The combination, with a desk, of a partition-support composed of sheet metal having parallel ribs struck up thereon, said ribs being flattened or struck down at the ends 45 thereof, so as to close the spaces formed by said ribs without obstructing the grooves between the same, substantially as and for the purpose specified.

2. The combination, with a desk the walls 50 of which are provided with angular grooves, of partition-supports having ribs struck up thereon, said ribs being flattened or struck down at the ends thereof, so as to close the 55 spaces formed by said ribs, but not obstruct the grooves therebetween, said flattened portion of the support being bent at an oblique angle thereto for insertion into the grooves in the desk-walls, substantially as described.

WILLIAM LUMLEY.
